UNITED STATES PATENT OFFICE

147,826

DESIGN FOR A TOY ANIMAL FIGURE

Elsie Ellen Wetmore, Los Angeles, Calif.

Application January 31, 1947, Serial No. 136,564

Term of patent 14 years

(Cl. D34—2)

To all whom it may concern:

Be it known that I, Elsie Ellen Wetmore, a citizen of the United States, residing at Los Angeles, in the county of Los Angeles and State of California, have invented a new, original, and ornamental Design for a Toy Animal Figure, of which the following is a specification, reference being had to the accompanying drawing, forming part thereof.

I claim:

The ornamental design for a toy animal figure, as shown.

ELSIE ELLEN WETMORE.
